CLAIM

The ornamental design for the bridal bow collector, as shown and described.

DESCRIPTION

FIG. 1 is a front view of the bridal bow collector showing my new design;

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken line showing of the bows in FIG. 2 is included for the purpose of illustrating environmental structure and forms no part of the claimed design.
